UNITED STATES PATENT OFFICE

128,492

DESIGN FOR A GAME BOARD

Paul Jolley, Ponderay, Idaho

Application February 3, 1941, Serial No. 98,714

Term of patent 14 years

To all whom it may concern:

Be it known that I, Paul Jolley, a citizen of the United States of America, residing at Ponderay, county of Bonner and State of Idaho, have invented a new, original, and ornamental Design for a Game Board, of which the following is a specification, reference being had to the accompanying drawing, forming a part thereof wherein:

I claim :

The ornamental design for a game board, as shown.

PAUL JOLLEY.
